UNITED STATES PATENT OFFICE.

H. RAYMOND ADAMS, OF MARSEILLES, ILLINOIS.

DOUBLE-ACTING PUMP.

SPECIFICATION forming part of Letters Patent No. 333,808, dated January 5, 1886.

Application filed September 19, 1885. Serial No. 177,605. (No model.)

To all whom it may concern:

Be it known that I, H. RAYMOND ADAMS, a citizen of the United States of America, residing at Marseilles, in the county of La Salle and State of Illinois, have invented certain new and useful Improvements in Double-Acting Pumps, of which the following is a specification, reference being had therein to the accompanying drawings.

10 This invention relates to certain improvements in double-acting pumps, which improvements are fully set forth and explained in the following specification and claims, reference being had to the accompanying drawings, making a part of this specification, in which—

Figure 1 represents a vertical cross-section of a deep-bored well, and a side view of the cylinder in the well, connected with a pump-stock by means of a pipe as it would appear 20 when ready for use. Fig. 2 is a side elevation of the pump-cylinder. Fig. 3 is a central vertical cross-section of the same. Figs. 4 and 5 are top plan views of the two annular valve-seats of the cylinder. Figs. 6 and 7 are central vertical cross-sections of the same. Fig. 8 is a top plan view of one of the annular valves of the cylinder. Fig. 9 is a side view of a ring, which is placed between the two annular valve-seats in the cylinder to hold them 25 the required distance apart. Fig. 10 is a plan view of the same; and Fig. 11 is a central cross-section of one of the annular valves, such as is shown in Fig. 8.

The construction of the cylinder is as follows: D represents a short section of the cylinder, having its inner ends screw-threaded for connecting it to the other sections of the cylinder through the medium of reduction-couplings. This short cylinder contains the two 30 valve-seats V' and Z' and their respective valves V and Z. These valves are held a proper distance apart by means of a thin band-ring, g'. (See Fig. 3.) The section D of the cylinder is connected with the cylindrical section B above by means of a reduction-coupling, E, and the section B forms chamber a above the valves. Valve-seat V' is held down to its proper position on ring g' in cylinder D by means of a second and similar band-ring, g, placed between said valve-seat and coupling E. The cylindrical section of the pump-cylinder

is connected at its lower end with the lower cylindrical section A by means of the reduction-coupling F, and this section A forms the chamber a² and contains the pump-cylinder 55 proper. A strainer, I, is attached to the lower end of the cylinder A, and furnishes means for supporting the pump on the bottom of the well, as well as to strain the water before it enters the pump. Valve-seat Z', (see Figs. 5 60 and 7,) has a somewhat large central opening, X, and a depending screw-threaded flange, X', on which the cylinder T is screwed in such manner as to hang suspended from said valve-seat centrally in chamber a², formed by cylinder 65 A. The annular valve-seat Z' is supported in its proper position on the reduction-coupling F. The annular valve-seat V' has a central opening, Y, (see Fig. 4,) smaller than opening X of valve-seat Z'. These openings through 70 said valve-seats permit the passage of reciprocating pipe G, as shown in Fig. 3, so its upper end is presented in chamber a and its lower end in chamber a². A lift-valve, J, is attached to the upper end of this pipe G, as 75 is also the pump-rod R, extending up to the pump-handle, and a double-acting plunger is attached to its lower end and reciprocates in the pump-cylinder T. The lower open end of pipe G is presented to chamber a³, 80 formed in said cylinder between said plunger and the clack-valve m at its lower end. This plunger has two annular flanged packings, b and b', (shown in Fig. 3,) so arranged that packing b will be brought into service on a 85 downward stroke of pipe G, and so packing b' will be brought into service on an upward stroke of said pipe. The pipe G is arranged to reciprocate through valve-seats V' and Z', to reciprocate plunger H in cylinder T. A packing such as is shown at W in Figs. 4 and 6, is 90 placed around pipe G on valve-seat V', and properly held in place by means of a ring, r, placed over said packing and firmly held down by screws passing into said seat, which packing is for the purpose of preventing too great wear on pipe G, and to prevent the backward 95 passage of water from chamber a.

To the lower end of cylinder T is attached a valve-seat, O, (shown in Fig. 3,) which has a 100 central opening, and is mounted by a clack-valve, m, which will open by suction when

plunger H is raised, and close immediately when the upward movement of said plunger ceases.

To the upper end of cylindrical section B is attached a reduction-coupling, C, for coupling it with the discharge-pipe P, which connects with the pump-stock above.

On the upper part of the annular valves V and Z are formed upwardly-projecting lugs d, as shown in Figs. 3, 8, and 11, for the purpose of preventing said valves from becoming non-seated by raising too high off their seats. The lugs of the lower valve, Z, will, when said valve is raised, engage with the lower part of seat V' above, and the lugs of valve V, when said valve is raised, will engage with the inner extending rim of the reduction-coupling E.

The operation of this device is as follows:

- 20 Assuming the cylinder to be submerged, and its chambers filled with water, as would be the case when placed in a well, as shown in Fig. 1. The normal position of the pump-handle is down, holding up the pump-rod R', as is shown in Fig. 1. In such case the plunger H in cylinder T would be near the upper end of said cylinder, reducing chamber a' therein to small proportions, and chamber a³ would be full of water. As the pump-handle is raised, plunger H is forced down to the position shown in Fig. 3 by its connection with pump-rod R', by means of which the water in chamber a³ is forced up through pipe G and out at valve J into chamber a and up pipe P to be discharged through the pump-spout. While this downward movement of plunger H is taking place valve V will close to support the water above it, and the downward suction in cylinder T, caused by the downward movement of plunger H, will raise valve Z, and cause water that has entered chamber a³ through strainer I to flow through the ports u, (see Fig. 5,) in valve-seat Z' and into chamber a' above plunger H. When the said movement of plunger H is stopped, valve Z will close to prevent the water from escaping back into chamber a², and valve J will also close to prevent water in chamber a from escaping back into chamber a³. When upward movement of plunger H takes place, valve V will rise, and water in chamber a' will be forced up through the ports n in valve-seat V' into chamber a and pipe P to be discharged through the pump-spout, and valve m below plunger H will open and water will be drawn up through strainer I and valve-seat O into chamber a³ of cylinder T, and be ready for another downward stroke of plunger H.

Fig. 3 represents the position of the parts when an upward movement of plunger H is first commenced, showing valve V open to permit an upward passage of water from chamber a', and valve Z closed to prevent its escape back through said valve. Said figure also shows valve m open to permit water to enter and fill chamber a³, so that the pump becomes double-

acting and discharges water from the pump-spout at each stroke of the pump-handle.

This pump is especially adapted to use in deep-bored wells of such small diameter that it is not practicable to insert more than one pump rod or pipe in the well, as is shown in Fig. 1.

Having thus described my invention, what I claim as new, and desire to secure by Letters Patent, is as follows, to wit:

1. The double-acting pump shown and described, consisting of the combination of the three cylinders A, B, and D, of different diameters, reduction-couplings E and F, for connecting said cylinders, reduction-coupling C, for connecting cylinder B with discharge-pipe P, strainer I, secured to the lower end of cylinder A, annular valve-seat V', having the ports n, central opening Y and packing W, annular valve-seat Z', having the ports u, central opening X, and depending central screw-threaded flange, X', annular band-rings g and g', annular valves V and Z, having packings V², held thereon by means of the annular rings 90 and screws V³, pump-cylinder T, having valve-seat O and clack-valve m at its lower end, and arranged to hang centrally in cylinder A from the depending screw-threaded flange of valve-seat Z', reciprocating pipe G, having the plunger H at its lower end and clack-valve J at its upper end, and pump-rod R, all arranged to operate substantially as and for the purpose set forth.

2. In the double-acting pump shown and described, the reciprocating pumping-pipe G, having the plunger H at its lower end and lift-valve J at its upper end, in combination with the central depending cylinder, T, having the clack-valve m at its lower end, cylinder A, and valve-seats V' and Z', and valves V and Z, all located at the upper end of said pump-cylinder T and centrally in the pump in cylinder D, as and for the purpose set forth.

3. The double-acting pump shown and described, formed of the three external cylinders, A, B, and D, of different diameters and connected by means of the reduction-couplings E and F, and connected with a supporting-strainer, I, at its lower end and a discharge-pipe, P, at its upper end, in combination with the annular valve-seat V', having the annular packing W, annular valve-seat Z', annular valves V and Z, having the valve-packings V³, said valve-seats and valves all being located in the central and largest cylinder, D, depending centrally-located pump-cylinder T, having the valve m at its lower end, and reciprocating pipe G, having the plunger H at its lower end and lift-valve J at its upper end, all arranged to operate as and for the purpose set forth.

4. In the double-acting pump shown and described, the internal cylinder, T, in combination with the external cylinders, A, B, and D, and their couplings, the annular valves V and Z and their seats V' and Z' and valve m, the pipe G, having the plunger H at its lower end, and

arranged to reciprocate in cylinder T, and having its upper end provided with valve J, to project into and reciprocate in the chamber *a* of cylinder B, in the manner substantially as set forth.

5. The combination of the cylinders A, B, D, and T, reduction-couplings C, E, and F, reciprocating pipe G, having the plunger H and valve J, valves *m*, V, and Z, valve-seats V' and Z', and O, band-rings *g* and *g'*, discharge-pipe P, and strainer I, and pump-rod R, all arranged to operate as and for the purpose set forth.

10. In the double-acting pump shown and de-

scribed, in combination with the external cylinders, A, B, and D, the central depending cylinder, T, having the lower valve, *m*, the reciprocating pipe G, having the plunger H on its lower end and valve J at its upper end, the annular valve-seats V' and Z', and the annular valves V and Z, all arranged to operate 15 substantially as set forth.
